UNITED STATES PATENT OFFICE.

ANTON WIDRICH, OF NEW YORK, N. Y.

POCKET-BOOK AND POWDER-PUFF.

1,049,184.

Specification of Letters Patent.

Patented Dec. 31, 1912.

Application filed July 1, 1912. Serial No. 706,899.

To all whom it may concern:

Be it known that I, ANTON WIDRICH, a citizen of the United States, and a resident of the city of New York, borough of Manhattan, in the county and State of New York, have invented a new and Improved Pocket-Book and Powder-Puff, of which the following is a full, clear, and exact description.

10 My invention relates to an improvement in pocket-books, and comprises an article of this description having a false bottom containing a powder puff, the bottom consisting of separable parts which can be opened to allow the powder puff to be used.

Reference is to be had to the accompanying drawings forming a part of this specification, in which the same characters of reference indicate the same parts in all the views.

Figure 1 is an end view of my invention; Fig. 2 is an end view showing the bottom thereof open to place the parts forming the puff in operative position; Fig. 3 is a side elevation of the same; and Fig. 4 is a sectional view on the line 4—4 of Fig. 3, showing how the combined pocketbook and powder-puff is made so as to combine the two in one and yet keep the parts separate from each other.

The body of the pocketbook may be of cloth or leather, and it comprises two sections shown at 1, united along their upper edges and the upper part of their side edges by means of metal rims 2. These metal rims are pivoted to each other upon pins 3 located about the middle of the sides of the pocketbook, and these rims are further provided with interlocking knobs 4, so that they can be closed together. The lower part of the sections or halves 1 forming the body contains a lining 5 which forms a false bottom 6 and is particularly shown in Fig. 4. The under side of this false bottom is provided with a puff-forming material 7, which covers the under side of the bottom, as shown, and the edges of the lining 5 coincide with the edges of the halves 1 of the body portion along the lower parts of the sides and bottom and are joined to metal rims 8, one of which is used for each of the sections 1, and which are pivoted to each other and to the rims 2 by means of the pins above mentioned. The lower rims 8 can be secured together by means of an ordinary

catch 9, which engages both of these rims and is pivoted to one of them as shown at 10.

It will be seen by referring to Fig. 4, that the false bottom 6 receives the coins, change and other articles which are carried in the pocketbook, the rims 2 permitting the insertion of such things when they are moved apart to permit the pocketbook to be opened. The lining 5 is secured to the sections or halves 1 all around its top edge, so as to prevent the contents of the pocketbook from slipping between this lining and the material forming the sections 1, and the upper edge of the lining at the point where it merges with the outer edge of the false bottom 6 is about on a level with the pivot pins 3.

When the puff is not to be used the arms 8 are secured together by the catch 9, but when occasion arises for using the puff the catch is disengaged and the rims 8 moved to the position shown in Fig. 2. The pocketbook may be filled or emptied at this time, and in either case the act of moving apart the rims 8 serves to open out the puff, as will be readily understood. The other part of the pocketbook then serves as a handle. When the puff is not in use it is only necessary to release the catch formed by the knobs 4 to move apart the rims 3 to allow coins or other things to be inserted into the pocketbook to be received upon the false bottom 6.

From the above description it will be seen that I have produced a simple and convenient article intended for the convenience of women. The invention can be carried about like an ordinary purse and can be used at an instant's notice.

Having thus described my invention, I claim as new and desire to secure by Letters Patent:

1. An improvement of the kind described comprising a body having a portion for forming a receiving or storage space, an oppositely-located portion for forming a powder puff, and means for covering and uncovering the said powder puff.

2. In an improvement of the kind described, the combination of a body comprising a pair of sections, a pair of rims secured to each section, one of said rims being secured to the top edge and the other rim being secured to the bottom edge, and the ends of said rims extending along the sides of said section and being pivotally secured

to each other and to the rims of the other section, means for securing the top rims and the bottom rims of the two sections together, and a web inside of said body uniting said sections forming a partition or false bottom, said web having puff-forming material secured to the lower face thereof.

3. In an improvement of the kind described, a pocketbook having a lining extending over the interior surface adjacent the bottom thereof, the upper edge of said lining being connected by a web forming a partition or false bottom, said lining being divided along the bottom of the pocketbook, 10 said partition and said lining having puff-forming material on the surface thereof, and 15 means for distending the lower part of the

pocketbook and said lining when the puff is to be used.

4. A pocket-book having a web dividing 20 the interior thereof into two parts, puff-forming material contained in said pocket-book on one side of the web, and means for distending the sides of the pocket-book on the said side of the web when the puff is to 25 be used.

In testimony whereof I have signed my name to this specification in the presence of two subscribing witnesses.

ANTON WIDRICH.
